UNITED STATES PATENT OFFICE.

FLOYD L. CHAMBERLAIN, OF WATERLOO, IOWA.

SUPPORTING DEVICE FOR WRINGERS.

Application filed March 21, 1927. Serial No. 177,054.

My invention relates to supporting devices for wringers and the like, and the object of my improvement is to provide means for detachably assembling a wringer with a supporting gear-casing, whereby the wringer may be easily and quickly mounted upon or demounted from the gear-casing.

This object I have accomplished by the means which are hereinafter described and claimed, and which are illustrated in the accompanying drawings, in which Fig. 1 is a side elevation of a metal frame wringer mounted detachably upon a gear-casing by my improved adapting means, Fig. 2 being a perspective view, fragmental, of the adapting means portion of the gear-casing, on an enlarged scale.

The wringer 1 may be of any type or construction, and on an end portion of its frame standards 2 may have above and below spaced pairs of apertured lugs 3 and 4.

Bolts 7 and 5 respectively traverse the apertures of said pairs of lugs, the bolt 5 seating a nut 6, while a handled nut 9 is seated on the bolt 7 for manual use.

The numeral 16 denotes a gear-casing with side opening covered by a closure plate 17. This gear-casing has a tubular depending part 18 fixed upon a supporting base-plate 19, such as is mounted upon the top part of a washing machine. The end wall of the gear-casing is apertured at 13 facing the wringer end standard 2, this aperture being traversed by a grooved end of a shaft section 14 carrying one of the gears in the casing, and the grooved end receives a mating projection on the abutting end of the shaft section which is the central shaft 15 of the lower wringer roll. These shaft connecting ends are shown in dotted lines in Fig. 1, while the grooved end of the shaft section 14 is shown in Fig. 2. The gear-casing 16 has inclosing flanges 10 projecting into contact with said standard 2. The side flanges are grooved

45 transversely at the top to supply downwardly curved recesses 12 to seat the upper bolt 7 while preventing egress of the bolt by longitudinal displacement. Said flanges are grooved at 11 near the bottom to provide horizontal recesses or seats for the lower bolt 5, which permits the bolt to be swung into

or out of these recesses 11, the bolt 7 serving as a pintle in the depressed inner ends of the upper recesses 12, the weight of the wringer keeping the bolt 7 from being lifted 55 out from the recesses by accidental contacts or the use of insufficient force. It should also be noted, that because of the overhang of the wringer relatively to the gear-casing 16, that the lower bolt 5 is thrust into the 60 grooves or recesses 11 and is held there to oppose ordinary thrusts in a contrary direction.

The wringer is mounted quickly upon the gear-casing by tilting the former to insert 65 the bolt 7 into the upper recesses 12, then swinging the wringer toward the gear-casing to engage the lower bolt 5 with the lower recesses 11. The nuts 9 and 5 may then be turned upon their bolts to clamp the apertured projections 4 and 3 respectively upon the opposite side flanges of the gear-casing.

The wringer may be easily removed by loosening the nuts on said bolts, and then swinging the wringer outwardly tiltingly to 70 release the lower bolt 5 from the lower straight recesses 11 before the upper bolt 7 is lifted out of the upper recesses 12.

Having described my invention, what I claim as new, and desire to secure by Letters 80 Patent, is:

1. The combination with a gear-casing, of a wringer frame having vertically spaced pairs of apertured lugs, bolts traversing said apertures, nuts mounted on said bolts, and said gear-casing having spaced flanges to fit between said lugs, the flanges having at the top downwardly curved opposite recesses and at the bottom straight horizontal opposite recesses to removably seat said bolts, whereby the upper recesses serve as seating hollows for the upper bolt as a pintle, and the lower bolt is retained in the lower recesses by the weight of the overhanging wringer.

2. The combination with a gear-casing, of 95 a wringer positioned in juxtaposition thereto, said wringer having an end standard in its frame abutting upon the gear-casing and having apertured lugs receiving the abutting part of the gear-casing matingly therebetween and in fitting contact, said gear-casing having a downwardly curved seat to receive

a bolt as a pintle for the wringer, a bolt traversing the apertures of said lugs and seated in said curved seat removably, a nut on said bolt to secure it in said lugs, said gear-casing having a recessed seat to receive a bolt traversing the apertured lower pair of said lugs, a bolt in said apertures, and a

nut on said bolt to secure the bolt in said lower lugs, the latter bolt being held in engagement with the lower recessed seat by the ¹⁹ gravity of the overhanging wringer.

In testimony whereof I affix my signature.

FLOYD L. CHAMBERLAIN.
